CLAIM

The ornamental design for an earbud case, as shown and described.

DESCRIPTION

FIG. 1 is a top, front, right-side perspective view of an earbud case;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The broken lines depict features of the earbud case that form no part of the claimed design.
